[57] CLAIM

The ornamental design for a clothing bottom design, as shown and described.

DESCRIPTION

FIG. 1 is a front, right side perspective view of a clothing bottom design, showing my new design;

FIG. 2 is a rear, left side perspective view thereof;

FIG. 3 is a front elevational view thereof shown in a flat and unfolded position; and,

FIG. 4 is a rear elevational view thereof shown in a flat and unfolded position.

The broken-lines shown in FIGS. 1 and 2 are for illustrative purposes only.
